C. W. HUTCHINSON.
TOY FLYING MACHINE MOTOR.
APPLICATION FILED APR. 19, 1920.

1,365,917.

Patented Jan. 18, 1921.

UNITED STATES PATENT OFFICE.

CHARLES W. HUTCHINSON, OF MILWAUKEE, WISCONSIN.

TOY-FLYING-MACHINE MOTOR.

1,365,917.

Specification of Letters Patent. Patented Jan. 18, 1921.

Application filed April 19, 1920. Serial No. 374,953.

To all whom it may concern:

Be it known that I, CHARLES W. HUTCHINSON, a citizen of the United States, and resident of Milwaukee, in the county of Milwaukee and State of Wisconsin, have invented certain new and useful Improvements in Toy-Flying-Machine Motors; and I do hereby declare that the following is a full, clear, and exact description thereof.

10 My invention refers to mechanism for winding elastic straps utilized as motors for flying machines or other self propelled toys.

The invention has for its primary object to provide a simple mechanism and effective 15 means for distending such straps or bands so as to increase the life of the same by avoiding twisting action or coiling of the same.

Other objects of my invention are:

20 To provide means for readily replacing the worn endless bands or straps;

To provide grips for the ends of the bands with brackets whereby said grips will resist cutting or wear at these points of strain;

25 To provide a toy vehicle having a reach rod or frame which has attached at one end a drum driven gear train unit and drive, and to the other end of the frame is attached one or a plurality of endless resilient bands having a flexible runner connecting these bands and drum whereby the flexible runner only will be wound upon the drum when the bands are distended;

30 To provide a tough flexible runner such as cat-gut or the like as a part of a resilient strap, the flexible portion being adapted for winding about the drum, whereby the resilient portion of this strap is subjected only to a working strain in a straight line, thus 35 avoiding twisting of the resilient material or coiling of the same which would result in deterioration after slight usage.

With the above and other objects in view, the invention consists in certain peculiarities 40 of construction and combination of parts which are fully set forth hereinafter with reference to the accompanying illustration and subsequently claimed.

The drawing illustrates an elevation of a 45 flying toy embodying the essential features of my invention, parts being broken away and in section to more clearly illustrate certain structural features.

Referring by characters to the drawing, 1 50 indicates a longitudinally disposed reach

bar which constitutes the frame member and has attached thereto a suitable horizontally disposed wing or plane 2 and a vane 3 at its rear end. The structure is also provided with a tail foot 4 and a forwardly positioned frame carrying supports for wheels 5. These elements may be of any type and constitute no part in my invention.

60 Mounted upon the forward end of the reach bar is a bracket 6 having a socket portion 7 which is fixed to the end of said reach bar and the bracket also forms journal bearings for the horizontally disposed short shaft 8, the outer end of which carries a wheel 9 of the propeller type. The 65 bracket is also provided with vertically disposed bearings 10-10 having a drum shaft 11, which drum shaft extends through the reach bar and carries a beveled gear wheel 12 that is meshed with a pinion 13 secured to the inner end of the wheel shaft. The 70 upper end of the shaft 11 is provided with a suitable winding key 13' and the lower end has secured thereto a drum 4, the same having secured thereto one end of a flexible 75 non-resilient runner 14', the same being preferably composed of some tough material such, for example, as cat-gut, wire or the like. The opposite end of this runner carries a metallic hook 15 that is protected by 80 a sheathing 15' which sheathing is of some soft material to prevent abrasion or wear.

85 Another hook 16 provided with a sheathing 16' secured to the rear end of the reach bar by means of a thimble connection 17 and 90 this pair of hooks are adapted to receive one of a series of resilient strips 18 which are preferably in the form of endless rubber bands. The normal length of these bands is considerably less than the distance between the rear anchor hook 16 and the drum 14 which is attached to the forwardly positioned train of gears.

95 Thus it will be seen that these rubber bands constitute a motive force whereby 100 their contractile energy is imparted to the drum, and through its gear connection rapid rotation of the propeller wheel is had. The primary idea in this construction is to arrange a means for distending the bands in a 105 straight line so as to avoid twisting of the same or winding them about the drum or other element whereby they would become deteriorated. In other words, it is a well known fact that rubber bands stand a great 110

amount of wear if they are simply distended and contracted, whereas under other conditions they will quickly deteriorate.

In the exemplification of my invention, as shown, the bands are only subjected to contraction and expansion in a straight line and since it is desired to wind the motor, the shaft 11 is simply revolved by hand, whereby the tough cat-gut, or other runner, only 5 is wound upon the drum while the bands are extended their full length. Hence it will be seen that owing to the tough material, from which the runner section of the flexible strap is made, that said runner will 10 last indefinitely, while the life of the bands, which are only stretched in a straight line, will be increased materially.

Further it is manifest that the bands can be renewed readily by simply assembling the 20 new set upon the hooks which are readily accessible and that this renewal of the bands can be effected by children or other persons not skilled in mechanics.

While I have shown this simple and practical arrangement of utilizing rubber bands as a motive force for propelling a flying machine toy, obviously I may utilize this same principle in other self propelled toy mechanisms without departing from the spirit of 25 my invention.

It is further understood that the drive gear shown may be varied to meet certain conditions without departing from the spirit of my invention, as for example, in some instances the propeller wheels may be connected directly to the drum shaft.

I claim:

1. In a flying toy having a reach bar provided with horizontally disposed forward 40 sustaining wings, and a vertically disposed guide vane at its rear end; the combination of a propelling mechanism comprising a

bracket mounted at the forward end of the reach bar, a propeller shaft journaled in the bracket, a drum having its shaft journaled in said bracket and in gear connection with the propeller shaft, a strap connected to the drum at its forward end and to the reach bar at its rear end, the said strap being composed of a resilient section and a 45 non-resilient flexible section, the flexible section being adapted for winding about the drum, whereby the resilient section may be fully distended between the drum and its rear anchored point for applying power to 50 said drum, incidental to the resilient section being contracted to its normal length.

2. In a flying toy having a reach bar provided with horizontally disposed forward sustaining wings and a vertically disposed guide vane at its rear end; the combination of a propelling mechanism comprising a thimble socketed upon the rear end of the reach bar and having a hook extending therefrom, a bracket having a body socket 60 fitted to the front end of said reach bar, a horizontally disposed propeller shaft journaled in the bracket, a vertically disposed drum carrying shaft journaled in said bracket, a gear connection between the propeller shaft and drum carrying shaft; a 65 non-flexible strap carried by the drum and adapted to be wound thereon, the strap having a hook at its free end and an endless resilient strap section connected to the strap 70 hook and to the thimble hook, the resilient strap when fully extended being arranged to approximately fill the space between the drum and rear reach carrying hook.

In testimony that I claim the foregoing I 75 have hereunto set my hand at Milwaukee, in the county of Milwaukee and State of Wisconsin.

CHARLES W. HUTCHINSON.
